UNITED STATES PATENT OFFICE.

JULIUS BUENO DE MESQUITA, OF BROOKLYN, NEW YORK.

SAFETY-RAZOR.

1,312,390.

Specification of Letters Patent. Patented Aug. 5, 1919.

Application filed March 31, 1915. Serial No. 18,295.

To all whom it may concern:

Be it known that I, JULIUS BUENO DE MESQUITA, a subject of the King of England, residing at Brooklyn, in the county of 5 Kings and State of New York, have invented certain new and useful Improvements in Safety-Razors; and I do hereby declare the following to be a full, clear, and exact description of the invention, such as 10 will enable others skilled in the art to which it appertains to make and use the same.

This invention relates particularly to certain improvements in the blade retaining clips of safety razor frames, and also to de- 15 tails of construction of the cap or cover plate for the blade.

The essential objects in view are the effective gripping of the blade regardless of variations in thickness of the parts, and the 20 facilitating of manipulation of the cap.

With these and further objects in view, as will in part become apparent and in part be hereinafter stated, the invention comprises certain novel constructions, combina- 25 tions and arrangements of parts as subsequently specified and claimed.

In the accompanying drawing:

Figure 1 is a plan view of a razor embodying the features of the present invention.

Fig. 2 is an edge view thereof.

Fig. 3 is a longitudinal section taken on the plane indicated by line 3—3 of Fig. 1 and looking in the direction indicated by the 35 arrows.

Fig. 4 is a transverse section taken on the plane indicated by line 4—4 of Fig. 1.

Fig. 5 is a detail perspective view of the spring strip detached.

Fig. 6 is a transverse section taken on the plane indicated by line 6—6 of Fig. 5.

For the sake of clearness of disclosure, the parts have been shown on a very much enlarged scale beyond the actual physical 45 structure as ordinarily constructed for use.

Referring to the drawing by numerals, 1 indicates the handle of a razor frame, detachably connected to the back plate 2 of the frame, which carries the blade supporting plate 3, terminating in the safety guard 4. At the rear edge, plate 3 is formed with eyes 5, in which is hinged the cap or cover plate 6. A spring 7 is fixed to the back plate 2 and has a free end portion disposed 50 in the path of movement of a rigid tab 8 preferably formed integral with the cap 6

and disposed to engage the spring 7 for springing the cap to and retaining it in a closed position, and for swinging the cap to an open position when being opened. A 60 spring 16 is fixed to the rear pendant or flange portion of the cap plate and is provided with free arms adapted to engage and press forwardly a blade resting on plate 3. The cap plate 6 is provided at each end with a terminal closing flange 9, the plate proper being disposed when closed to extend from its rear edge flange forwardly to the front edge of the plate so that the terminal flanges 9 taper forwardly. Adjacent the 65 forward end of each flange 9, the material of the flange is formed with a laterally extending lip or gripping lug 10, preferably stamped from the material of the flange as best seen in Fig. 2 so that when the operator 70 wishes to swing the cap plate 6 from its closed position to its open position, he can do so readily by grasping the cap endwise between the thumb and one of the fingers, the lug or projection 10 at one end being en- 75 gaged by the thumb, and that at the other end being engaged by the finger. As the cap often must be opened while more or less moist and sometimes coated with soap, the lugs or projections 10 are very desirable as 80 effective means for enabling manual swinging of the cap on its hinge.

In the construction of what is known as "wafer blades" difficulty has been experienced in obtaining blades of uniform thickness and perfectly flat, and occasionally where this type of blade is provided with a folded backing strip, the amount of irregularity in the matter of effective thickness in applying the blade to a razor frame is augmented. Accordingly, difficulty has been experienced in retaining razor blades in place even though spring clips have been employed designed to respond to irregularities and still effect a gripping action on the 90 blade. To accomplish the best results in the easiest manner and with a characteristically inexpensive apparatus, I find that blade engaging clips should be employed having a certain amount of freedom for bodily movement in addition to the capacity for further movement under spring tension.

Plate 3, near its forward edge, is provided with detent lugs 11, 11, disposed to be engaged by the razor blade 12 for retaining 100 the blade against forward movement and for coöoperating with the spring 16 in hold-

ing the blade in operative position. Plate 3 is provided at its ends with notches 13, 13, and a strip of spring material forming a spring body 14 is arranged with its end 5 portions bent through the notches 13 to form blade engaging clips 15, the body of the spring 14 extending beneath the plate 3 and the end portions being formed into upwardly extending hooks. As best seen 10 in Fig. 6, each clip 15, formed by the respective hook, has its under face slightly inclined to correspond substantially with the inclination of the upper face of razor blade 12. The spring body 14 is not fixed to plate 15 3 but is held in place by the engagement of the hook ends 15 with notches 13, the body being formed at its intermediate portion 20 with an upward offset 14' so that the said offset may rest against the under face of plate 3 while the end portions are spaced therefrom and are left free for spring action in addition to which the member or body 14 as a whole is capable of a certain amount of bodily shifting both vertically and longitudinally. Thus the clips 15 accommodate 25 themselves to and effectively grip any blade engaged thereby regardless of variations in relative thickness.

The cap 6 being in the open position, the 30 razor blade 12 is placed flatwise against the rear portion of plate 3 and is slid forward beneath the clips 15 until the front edge of the blade strikes the detent lugs 11, and then the cap 6 is swung to its closed position and 35 there retained by the engaging spring 7 so that the blade is firmly retained against edgewise movement by the lugs 11 at its front edge and the spring 16 at its rear edge, and is held against lateral, that is vertical, movement by the engagement of the 40 end portions 6', 6', of the front edge of cap 6 with the front portion of the blade and the engagement of clips 15 with the ends of the blade at intermediate points thereof. 45 The intermediate portions of the front edge of cap 6 are spaced slightly above the blade, say from one to two thousandths of an inch, so as to avoid any undesirable deflection of the blade. The blade 12 in being applied 50 and pressed forward to its final position, when passing under the clips 15, elevates the same until the free play or bodily movement of the spring member 14 is taken up and the upwardly bent portion 14' is caused to 55 strike the under face of plate 3, and then the further movement of the blade to position is effected with a continued compensating

springing action of the end portions of the spring body 14.

What I claim is:—

1. The combination with a razor frame, 60 of a spring comprising a strip of material extending across the under face of the razor frame and having an upwardly offset portion between the ends of the razor frame upstanding in position to engage the under portion of the razor frame and leaving end portions of the strip spaced from the frame and free for vibration, the end portions of the strip being bent about the ends of the 70 razor frame and into position overhanging the razor frame for clamping the ends of a razor blade down against the frame.

2. The combination with a razor frame 75 having notches in its opposite ends, a spring bearing against the underside of the frame and adapted to slide thereover, and clips carried upon the opposite ends of the spring and extending through the notches at the 80 ends of the frame and being overturned against the upper side of the frame for yieldably engaging a razor blade fitted to the frame.

3. The combination with a razor frame 85 formed with a notch at each end, of a spring plate extending across the frame therebeneath and having terminal portions bent about the ends of the frame and through the notches for forming blade engaging clips above the frame, the terminal portions being 90 of greater length than the depth of the notches to retain the spring plate on the frame, and the spring plate being formed with an intermediate offset portion extending upwardly toward the frame to free the 95 ends of the spring for flexing and binding the blade to the frame.

4. In a safety razor, the combination with 100 a frame, of a cap plate for the razor blade sustained by the frame, the cap plate having pivotal connections with the frame at its rear portion and disposed for having the end portions of its front edge engage a blade sustained by the frame for preventing dislocation thereof, intermediate portions of 105 the front edge of said cap plate being spaced from the blade to prevent flexing of the cutting edge of the blade by the cap plate.

In testimony whereof I affix my signature in presence of two witnesses.

JULIUS BUENO DE MESQUITA.
